G. C. BOVEY.
Street-Car Heater.

No. 227,345.

Patented May 11, 1880.

FIG. 2.

FIG. 4.

UNITED STATES PATENT OFFICE.

GEORGE C. BOVEY, OF COLUMBUS, ASSIGNOR TO GEORGE B. KERPER, OF CINCINNATI, OHIO.

STREET-CAR HEATER.

SPECIFICATION forming part of Letters Patent No. 227,345, dated May 11, 1880.

Application filed January 24, 1880.

To all whom it may concern:

Be it known that I, GEORGE C. BOVEY, of Columbus, Franklin county, Ohio, have invented certain new and useful Improvements in 5 Street-Car Heaters, of which the following is a specification.

This is an improvement on Letters Patent No. 211,963, granted to myself and George B. Kerper, February 4, 1879, for street-car heater; 10 and the present invention consists in constructing the heater in such a manner as to cause it to occupy less space both underneath and within in the car or other vehicle, and at the same time all danger of setting fire to the car is 15 completely obviated.

In the annexed drawings, Figure 1 is a vertical section through the lower part of a street-car provided with my heater, a portion of the latter being broken away and shown in section. 20 Fig. 2 is a vertical section of the heater taken in the plane of the grate-bars, the magazine and suspension-rods being omitted. Fig. 3 is a plan of the apparatus; and Fig. 4 is a horizontal section of the same, the section being 25 taken in the plane of the air-inlets of the hot-air chamber and the central portion of the apparatus being broken away.

A B C represent, respectively, portions of the floor, side, and one seat of a street-car or 30 other passenger-vehicle, a suitable opening being made in said floor to admit the heater, which is constructed as follows:

D represents a fire-box having a door, d, 35 grate-bars E, and ash-pit F, which latter can be emptied by simply opening a trap, G.

Located a suitable distance from box D, and surrounding three sides of the same, is a partition or wall, H, whose opposite ends are secured to the front plate of the heater in the 40 manner shown in Fig. 4, while the upper and lower margins of this partition are attached to ribs or lugs projecting from the top and bottom plates of the fire-box, as represented in Figs. 1 and 2. Furthermore, this partition 45 is furnished with air-inlets h, which may be made in both of the sides and also in the back of the same; or, if preferred, these inlets may take the shape of slots h', as represented in Fig. 4, which slots may be located near the 50 front plate of the apparatus, to compel the air

to traverse a very circuitous route in passing through the heater. The annular space thus afforded between said partition and fire-box constitutes the hot-air chamber I.

The extreme outer casing or jacket, J, is 55 composed of one or more sheet-metal plates united to the front of the heater in the manner shown in Fig. 4, and securely riveted or bolted at j to the marginal flanges of the top and bottom plates of the fire-box D. This 60 jacket incloses a space, K, known as the "cold-air chamber," which chamber has inlets k of any shape. Said jacket projects some distance above the top plate of the heater, as at L, the margins of this extension being bent down at 65 l, and then nailed or screwed to the car-floor, as shown in Fig. 3. Evidently this bent portion or flange l will be sufficient to hold the heater firmly in position, provided the jacket is made of moderately thick metal; but in order to render the attachment of the heater 70 more secure a number of stirrups or slings or suspension-rods, M, may be employed, their upper ends being bent down and attached to the floor at m, while their lower ends, m', grasp 75 the margins of the jacket and the bottom flange of the fire-box, as seen in Fig. 1.

If preferred, the rivets or bolts j, that unite said jacket and flanges, may also pass through these suspension-rods. The fire-box D is 80 surrounded with a dome, N, to which is applied a smoke-pipe, O, the latter being, preferably, carried along underneath the seat C, and thence up at the corner of the car or on the outside of the same, as shown in my old patent. Cast 85 with or otherwise applied to this dome is an inclined chute or magazine, P, having near its lower end a gate or cut-off, R, whose handle r is to be engaged with a rack, S, or other device capable of maintaining said gate in a suitable position to regulate the flow of coal from 90 said magazine to the fire-box. T is the charging-door of this magazine.

Openings U are made in the top plate of the heater immediately over the chamber I, to 95 allow the warm air to escape directly into the car.

The dotted lines V (seen in Fig. 2) indicate the position of a shield or guard that may be attached to the floor and seat of the car to pre- 100

vent the passengers' feet or garments coming in contact with the heated dome.

W W' represent the customary internal wheel-guards of a street-car.

5 By referring to Fig. 2 it will be seen that cold air enters at inlets *k*, then descends and passes through openings *h* into chamber *I*, where the air becomes heated by contact with fire-box *D* before escaping at the outlets *U*, as indicated by arrows in said illustration. Consequently this part of the apparatus insures a copious supply of pure warm air to the car or omnibus or other vehicle to which the heater may be applied, and at the same time heat is 15 radiated from the dome *M* and pipe *O*. One advantage of this form of heater is that it is located wholly under one of the seats, while in my old patent the apparatus is represented as extending completely across the car, and 20 occupies considerable space under both seats. Now, this old arrangement, besides being complicated, heavy, and expensive, is also objectionable on account of it being in the way of the brake attachments on some forms of cars. 25 Furthermore, the old apparatus concentrates too much heat at one place, and is liable to set fire to the straw in the cars; but all of these objections are obviated by the present construction, which affords a cheap, simple, 30 and light apparatus that is situated wholly under either of the car-seats, and does not in the least interfere with any form of brake attachments.

Another advantage is its perfect safety from 35 fire, as the prolongation *L* of the external jacket, *J*, prevents any appreciable degree of heat being communicated from the apparatus to the car-floor or to any straw or other covering spread upon the same.

40 A still further advantage results from the use of magazine *P* and its accessories, as the gate *R* can be so adjusted as to insure a continuous supply of a greater or less quantity

of fuel to the fire-box *D*, the vibrations of the car causing a regular flow of coal down said 45 inclined chute.

If preferred, the door *T* of this chute may be omitted, and the magazine may be extended up through seat *C*, as shown at *X*, a trap-door being in this case hinged to the seat, so as 50 to afford facility for charging said fuel-chamber *T*. Finally, the dome may be omitted.

I am aware it is not new to surround the furnace of a car-heater with a partition inclosed by an outer jacket, as such a construction is 55 seen in Letters Patent No. 67,770, issued August 13, 1867, to W. G. Kendrick. Therefore my claim to this feature of the invention is expressly limited to a street-car heater whose furnace has an external fire-door, an intermediate partition, and an outer jacket, which jacket is carried up a sufficient distance above the furnace or fire-box to prevent heat being communicated to the floor of the car, as herein described and illustrated. 60

65 I claim as my invention—

1. A street-car heater consisting of a furnace, *D*, having an external fire-door, *d*, partition *H*, hot-air chamber *I*, cold-air chamber *K*, inlets *h k*, dome *N*, inclined magazine *P T*, and ventages *U*, the outer jacket, *J*, of said cold-air chamber being extended above the fire-box at *L* and attached to the car-floor at *l*, as herein described, and for the purpose set forth. 70

2. In combination with a car-heater of the 75 class specified, the outer jacket, *J*, and suspension-rods *M*, which rods are attached to the floor at *m* and are secured to the heater by the same bolts or rivets, *j*, that unite the jacket to the fire-box, as herein described. 80

In testimony of which invention I hereunto set my hand.

GEORGE C. BOVEY.

Witnesses:

JAMES H. LAYMAN,
G. B. KERPER.
